FIG. 7

UNITED STATES PATENT OFFICE.

HERMAN C. HIRSCHY, OF DULUTH, MINNESOTA.

WASHING MACHINE.

Application filed January 23, 1928. Serial No. 248,830.

My invention relates to the type of washing machine shown and described in my pending application for Letters Patent of the U. S. Serial Number 737,832, filed September 15, 1924.

The claims of this pending application are directed to improved means for mounting the agitator blades to the end that these blades can be easily and quickly seated in the under side of the agitator disk and as readily removed for repair or renewal purposes.

My present invention contemplates a simple inexpensive means for so mounting the agitator blades and a means that will form a very simple but substantial support for the blades, and at the same time will not add materially to the expense of manufacture of the agitator.

Other objects of the invention will appear from the following detailed description.

The invention consists generally in various constructions or combinations, all as hereinafter described, and particularly pointed out in the claims.

In the accompanying drawings forming part of this specification:

Figure 1 is a sectional view of a tub and agitator embodying my invention;

Figure 2 is a bottom view of the agitator;

Figure 3 is a sectional view on the line 3-3 of Figure 1;

Figure 4 is a detailed view illustrating a modified construction of the blade supporting means;

Figure 5 is a similar view showing another modification;

Figure 6 is a sectional view of still another modified means for supporting the blade;

Figure 7 is a detailed sectional view showing still another modification in the form of the blade supporting fingers or tongues.

In the drawing, 2 represents a washing machine tub, preferably of sheet metal, though any other suitable material may be used, and the tub may be of any suitable size. It is preferably of the form shown in Figure 1, with an upper portion 3 having inwardly projecting walls overhanging the interior of the tub and forming an opening 4 which, when the tub is in use, is closed by a suitable cover (not shown). Within the tub, I provide an upright standard 5 secured to the tub bottom by suitable means

such as lock nut 6 and an interiorly arranged flange (not shown).

A suitable stuffing box 7 is provided at the upper end of the standard and a drive shaft 8 projects up through the standard and the stuffing box, and has an upper portion 9 preferably rectangular in cross section at the base of which rectangular portion is a circular flange 10. The driving shaft may be brought down through the top of the tub if preferred. I merely illustrate one arrangement in this case as both methods are common in washing machines.

A cone 11 encircles the lower portion of the drive shaft and is seated on the bottom of the tub, this cone forming the subject-matter of U. S. Patents No. 1,336,781 and No. 1,349,338, and I make no claim broadly to the same herein.

A block 12 has a socket 13 to receive the upper end of the drive shaft, a shoulder 14 being formed in the walls of the socket to rest on the flange 10 and support the block for oscillation with the drive shaft, this shaft having a reciprocating oscillating movement to impart the desired stroke to the agitator.

15 represents a disk preferably of metal, and 16 is a dome thereon overhanging the central opening 17 of the disk. A box 18 is centrally mounted on the dome and depends therefrom, with parallel side walls adapted 85 to fit snugly the correspondingly shaped walls of the block 12 and allow the disk or agitator to rise and fall in the operation of the machine and adjust itself vertically to the volume of clothes beneath it in the tub.

When there is a considerable body of clothes in the tub, the agitator will be raised, and if only a few clothes are being washed, then the agitator will automatically descend within the tub.

The block 12 is preferably provided with a lifting finger piece 19 by means of which the agitator may be conveniently handled to place it in its working position in the tub or remove it therefrom.

While the box 18 is free to rise and fall on the block 12 in the operation of the agitator, its walls will be at all times in contact with the block and a rocking movement will be imparted to the agitator at all points in its vertical movement.

Whenever desired, the entire device 100 may be easily and quickly detached from the driving shaft by grasping the finger grip 19 and pulling upwardly thereon.

On the under side of the agitator disk, I provide a series of seats or holders for the agitator blades. There are preferably four of these holders extending radially on the 5 agitator disk, but this number may be varied if desired and preferably these holders are equally spaced apart on the disk.

Referring now to Figure 2, the holder proper comprises a radial opening which I 10 will designate by reference numeral 20, the same numeral being used for all of the holders as they are of the same construction in this figure. The holders are preferably open at their inner ends to allow the convenient insertion of the agitator blades, and as shown plainly in Figure 1, a depending wall 21 is provided at the outer end of each holder to form a stop against which the end of the blade is seated when in its working 20 position.

When the agitator is in operation centrifugal force will tend to hold the blades outwardly against the walls 21 and the inward movement of the blades to a point where 25 they might become separated from the holders will be prevented by the cone 11, the wall of which will be adjacent the inner portions of the blades as shown plainly in Figure 1. Upon removing the agitator disk 30 from the machine it will be a simple matter to release any one or all of the blades from the holders and detach them from the disk should repairs or substitution be necessary.

The agitator disk preferably has openings 35 formed therein at this point with cross bars 22 connecting the side walls of the openings as shown plainly in figures 1 and 4, and on each side of these openings, I provide inwardly turned converging flanges 23, having lugs 40 or tongues 24 formed thereon at intervals. The blades which I prefer to provide in connection with this agitator, I designate by reference numeral 25, and they are preferably of the shape shown in Figure 1, having 45 downwardly and outwardly inclined lower edges 26 and provided at their upper edges with heads 27 having flaring walls, their angle of divergence corresponding substantially to the angle of the flanges 23 so that 50 when the heads of the blades are slipped between these flanges they will fit snugly against them and be firmly seated at this point, while the principal part of the blade will depend within the tub in position to engage the clothes. The blades are made of 55 any suitable material, generally of rubber, having a certain degree of flexibility, but I do not confine myself to this material as any suitable substance may be used and the 60 blades may be flexible or not as preferred and their shape may be varied though I prefer to use substantially the form shown herein. When the blades have been inserted into the holders, the tongues or lugs 23 are 65 squeezed together so that they will grip and

firmly hold the blades in the operation of the machine. Of course whenever desired, the tongues may be pressed apart and the blades easily and quickly removed from their seats in the agitator.

70

In Figure 4 I have shown a slight modification which consists in providing a rigid flange 28 on one side of the holder opening, while the other side is equipped with the flexible tongues 29 adapted to be pressed inwardly to grip the head of the blade and clamp it securely against the opposite flange.

75

In Figure 5 I have shown a plate 30 provided with slots 31 to receive adjusting screws 32, said plate when the screws are 80 loosened, being capable of adjustment so that the lugs or tongues 24 thereon can be moved towards or from the corresponding lug or tongue on the other side of the holder seat.

85

In Figure 6 I have shown another modification which consists in providing a channel bar 33 having converging walls 34 between which the agitator blade is held. Suitable means such as a bolt 35 passes through the channel 33 and is provided with 90 a lock nut 36 by means of which the bolt can be tightened or loosened in mounting the channel bar on the agitator disk or removing it therefrom.

95

In Figure 7 the seat for the agitator blade 95 is shown with converging walls 37, each provided with a point or brad 38, which when the walls are pressed together, will dig into the head of the agitator blade and hold it securely. Whenever these walls are separated, the points or brads will be removed from the surface of the blade to permit convenient separation from the agitator.

100

By making the blade holders in the form shown herein and described, the user of the 105 washing machine can with comparatively little effort, remove a worn or broken blade and substitute another therefor, and this may be accomplished with little effort and by the use of a single tool.

110

The blades as shown plainly in Figure 1 depend a considerable distance within the tube and during the oscillation of the disk will engage the clothes and move them back and forth in substantially the same manner 115 as shown and fully described in my application No. 737,832 above referred to. In various ways the details of the holders and the manner of fastening the blades therein may be modified and still be within the scope of 120 my present invention.

115

I claim as my invention:

1. An agitator member having a pair of elements opposingly related to define a way, substantially parallel with the face of the 125 agitator member, at least one of said elements being adjustable to change the width of the way, and a finger having a portion lying within the way and clampingly engaged by said elements.

130

2. An agitator member having a pair of elements opposingly related to define a way, substantially parallel with the face of the agitator member, at least one of said elements being adjustable to change the width of the way, and a finger having a portion lying within the way and clampingly engaged by said elements and secured thereby against movement lengthwise of the way, and said elements being formed to secure the finger against movement in a direction substantially perpendicular thereto.
3. An agitator member having a pair of elements opposingly related to define a way, substantially parallel with the face of the agitator member, at least one of said elements being adjustable to change the width of the way, and a finger having a portion lying within the way and clampingly engaged by said elements, and secured thereby against movement lengthwise of the way, and said elements being convergent in a direction away from said agitator member to secure the finger against movement in a direction substantially perpendicular thereto.
4. An agitator member having a pair of elements opposingly related to define a way, substantially parallel with the face of the agitator member, at least one of said elements being adjustable to change the width of the way, and a finger having a portion lying within the way and clampingly engaged by said elements and secured thereby against movement lengthwise of the way, at least one of the elements being formed from bendable material to permit way width-adjustment and obtain clamping action.
5. An agitator disk having a way formed by opposed elements at least one of said elements being adjustable in a direction substantially parallel to the face of the disk to change the width of the way, and a finger of compressible material having a portion lying within the way and secured by the compressive action of the way-forming elements.
6. An agitator disk having a way formed by opposed elements, at least one of said elements being adjustable to change the width of the way, and a finger of compressible material having a portion lying within the way and secured by the compressive action of the way-forming elements, at least one of the way-forming elements being formed from bendable material, to permit way width-adjustment, and obtain clamping action.
7. An agitator member having a pair of elements opposingly related to define a way, substantially parallel with the face of the agitator member, at least one of said elements being adjustable to change the width of the way, and a finger having a portion lying within the way and clampingly engaged by said elements and secured thereby, said elements being integral with said agitator member and at least one of the elements being formed to permit way width-adjustment, and obtain clamping action.
8. An agitator member having a pair of elements opposingly related to define a way, at least one of the elements being adjustable to change the width of the way, and a finger having a portion lying within the way and clampingly engaged by said elements and secured thereby against movement lengthwise of the way, and said elements being formed to secure the finger against movement in a direction substantially perpendicular thereto.
9. An agitator member having a pair of elements arranged on one of its faces, said elements opposingly related to define a way, at least one of the elements being adjusted to change the width of the way, and a finger having a portion lying within the way and clampingly engaged by said elements to extend in direction substantially perpendicular to the face of the agitator member.

In witness whereof, I have hereunto set my hand this 9th day of January, 1928.

HERMAN C. HIRSCHY.
